(57) **CLAIM**

We claim the ornamental design for a sample collection device of an analyte detection system, as shown and described.

DESCRIPTION

FIG. 1 is a top, front, right side perspective view of a sample collection device of an analyte detection system according to an exemplary embodiment;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The dash-dash broken lines represent portions of the sample collection device of an analyte detection system that form no part of the claimed design. The dash-dot lines define the boundaries of the claimed design.
